FILLING MACHINE FOR GAS MASK
CANISTERS

Stuart M. Jessop, Baltimore, Md.

Application May 2, 1940, Serial No. 332,918

12 Claims. (Cl. 226—96)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a filling machine for gas mask canisters. These canisters are connected with the facepieces of gas masks and are so arranged that all inspired air passes through and is purified by the canister.

Gas masks canisters usually contain a quantity of granular activated charcoal which extracts harmful gases and vapors as the air passes through it. This charcoal must be firmly packed into the canister in order that there will be no movement of the charcoal which might cause the formation of channels through which the inspired air would pass without being purified. However, the packing must not be strong enough to crush the granular charcoal.

An object of this invention is to provide an automatic machine for filling and packing granular absorbents into gas mask canisters.

Another object of this invention is to provide an automatic machine for filling granular absorbents into a plurality of gas mask canisters while the canisters are caused to vibrate to thus settle and pack the absorbent.

Another object is to provide a filling machine wherein a plurality of gas mask canisters are filled with absorbents while rotating about a central axis and are simultaneously vibrated vertically, and wherein each canister is released from the vibrating mechanism as it arrives at a station for removal from the machine, whereby the packed absorbent is not disturbed.

A further object is to provide a machine for filling canisters with granular absorbents and which is fully automatic except for the placing of empty canisters therein and the removal of filled canisters.

These and other objects will be apparent from the following description and claims when considered with the accompanying drawings wherein

Figure 1 is a front elevation of the machine.

Figure 2 is a top plan.

Figure 3 is a side elevation.

Figure 4 is an enlarged section on line 4—4 of Figure 3.

Figure 5 is a part section on line 5—5 of Figure 4.

Figure 6 is a perspective view of a stationary member forming part of a valve assembly.

Figure 6A is a perspective view of a slide member forming part of said valve assembly.

2

Figure 6B is a view similar to Figure 6 and showing a second stationary member of said valve assembly.

Figure 6C is a perspective view of a perforated valve plate.

Figure 7 is a side elevation of the cam for controlling the vertical position of the canisters in the machine.

Figure 8 is a broken plan of the feed hopper for the granular absorbent.

Figure 9 is a section on line 9—9 of Figure 8.

In brief, the present machine has a horizontally rotatable carrier upon which is supported ten canisters to be filled. At an operator's station, 15 one filled and packed canister is removed and an empty one inserted in the carrier. As the empty canister is rotated away from the operator's station, a feed mechanism automatically opens to allow granular charcoal to fall into the canister, 20 and at the same time all canisters, except the one at the operator's station, are vibrated vertically to cause the material to pack. As a filled canister approaches the operator's station, the feed valve closes, and the canister ceases to vibrate.

Referring now to Figs. 1, 2 and 3, the frame of angle or channel members 1 supports a motor 2 which drives a reduction gearing 3, shaft 4 and pulley 5. Pulley 5 rotates carrier 6 by way 30 of drive belt 7. The canisters being filled are carried beneath carrier 6, as later described.

The granular absorbent, such as activated charcoal, is fed into an annular channel hopper 8 through pipes 9 and 11, by gravity. Hopper 8, 35 shown more in detail in Figs. 4 and 8, is carried by carrier 6 by means of bolts 12 (Fig. 4) and therefore rotates with the carrier. Feed pipes 9 project into the open top of hopper 8 and these pipes do not rotate. Hopper 8 has a plurality of 40 openings 13 in its bottom, each opening communicating with a separate feed box 14. One such feed box is provided for each canister mounted on carrier 6, there being ten such boxes in the embodiment shown.

45 Beneath each filling or feed box 14 is mounted a canister 15. These canisters are cans having closed bottoms and open tops, the walls being formed of perforated metal, and are substantially rectangular in cross section with rounded corners. The granular charcoal is fed by gravity from boxes 14 into canisters 15 through openings in rotary carrier 6, as follows: Referring to Figs. 4 and 6, carrier 6 has ten plates 16 secured 50 in alignment with boxes 14, each plate having a

series of openings 20 therethrough. Plates 16 are cupped on their lower surfaces as seen in Fig. 4 to receive the upper ends of the canisters 15. Above plates 16 are cut-off valves each comprising stationary plates 17 and 18 and movable valve plates 19 between plates 17 and 18.

Feed boxes 14 contact with plates 17, the open bottoms of these boxes surrounding openings 21 in these plates. Lower plate 18 has a series of openings 22 aligned with openings 20 of plate 16. Valve plates 19 are unperforated and are adapted to slide radially on rotary carrier 6 to close or open communication between boxes 14 and canisters 15. Plates 19 have rollers 23 mounted on posts 24 these posts engaging in slots 25 in plates 17 and 18 in order to guide plates 19. Valve plates 19 are actuated by engagement of cams with rollers 23, as hereinafter described.

In order that the granular charcoal as received in hopper 8 may be fed through the feed openings 13, the bottom of the hopper is provided with a series of sloping surfaces, as seen in Figs. 8 and 9. These surfaces are formed by a series of pyramids 25 between openings 13, with their high portions between the openings, and sloping down to the openings.

Referring to Fig. 4, rotary carrier 6 is secured to a hub 26 loosely journaled on a central shaft 27. Hub 26 has an inwardly extending shoulder 28 resting on a flange 29 of an electromagnetic vibrator 31. Thus carrier 6 may rotate freely and may be reciprocated by vibrator 31.

The supports for the ten canisters carried by carrier 6 are as follows. Referring to Fig. 4 where in one support is shown, a support shaft 32 is secured to carrier 6 adjacent each filler box 14. Each shaft 32 has slidably mounted thereon a canister support 33 having outwardly projecting arms 34 adapted to receive and support the lower end of canister 15. Canister support 33 is biased upwardly by a coiled spring 35 surrounding shaft 32 and supported at its lower end by bolt 36 threaded in the end of the shaft. A key 37 prevents rotation of support 33 on its shaft.

Each canister support 33 has a spring clip to retain its canister 15 in position. As seen in Fig. 4 each canister has a bottom with an outstanding flange 38. The spring clips have two arms 39 of flat strip metal so spaced that they engage over flange 38 of each canister to press the same against support arms 34. The spring clips are pivoted on posts 41 for tilting movement and are biased by springs 42 engaging their upper surfaces.

In order that vertical vibration of each canister may be prevented when it rotates to the operator's station, each canister support 33 has a roller 43 which engages a cam 44 (see Fig. 7). Cam 44 comprises two downwardly sloping surfaces 45 connected by a flat surface 46, projecting from an annular flange 47 of collar 48. The downwardly sloping surfaces 45 serve to force the cam follower 43 vertically downward, thus lowering the canister holder 34 and the canister 15 down and away from the rotary carrier 6. Collar 48 is secured to stationary shaft 27, as by set screw 49, Fig. 4. From the above construction, it will be seen that as the carrier 6 rotates, the rollers 43 on the canister supports 33 successively engage cam 44 and are forced downwardly against tension of springs 35. This movement lowers each canister 15 out of engagement with cup 16, so that it may be removed and an empty one put in place.

The cam 44 is so positioned on shaft 27 that each canister is lowered at the operator's station. When each canister is lowered, it is held against vertical vibration, since although the depending shaft 32 moves vertically, the canister support 33 does not so move and shaft 32 merely slides vertically through canister support 33.

In order that the feed of granular absorbent may be cut off from each filled canister as it approaches the operator's station and opens as the empty canister moves away, the following mechanism is used. Extending across the front of the machine is a frame member 51 upon which are secured two inwardly extending arms 52 and 53 which support cams for operating the cut-off feed valves. As seen in Fig. 5, arm 52 has a post 54 upon which is pivoted a cam 55 which carries a pin 56 at its opposite end. Pin 56 projects freely through an upstanding flange 57 on arm 52 and is surrounded by coil spring 58. Cam 55 is thus biased outwardly to a point determined by a nut 59 on pin 56 and may pivot inwardly a short distance.

As carrier 6 rotates, the roller 23 on each valve member 19 engages cam 55 and valve 19 is pushed inwardly to closed position. Cam 55 is resiliently pivoted, since some of the hard granular material will be in the path of valve 19 and must be pushed aside or crushed. A more gradual movement of the valve is obtained by this mounting. By the time the carrier 6 has rotated so that a roller 23 has cleared cam 55, valve 19 is completely closed and remains in this position during rotation of its canister carrier past the operator's station.

Beyond the operator's station, an opening cam 61 is positioned on arm 53. Cam 61 comprises a vertically extending flange on arm 53, angularly positioned so that each roller 23 will engage the outer surface thereof and the corresponding valve 19 will be opened.

Referring again to Figs. 1, 2 and 3, a pair of vertical conduits 62 are connected to a vacuum exhaust, their lower ends being turned horizontally at 63 beneath rotary carrier 6. Most of the fine particles of absorbent are drawn upward through these conduits. A catch pan 64 is positioned below carrier 6 to receive large particles of absorbent dropped from the machine.

Operation.—The operator starts motor 2 to thereby rotate carrier 6 in the direction shown by the arrows, Fig. 5. Granular absorbent, such as activated charcoal, is fed into pipe 11 and thereby flows into the channel hopper 8 and is evenly distributed therein, since hopper 8 is rotating. The operator slips an empty canister 15 on the canister support arms 34, the flange 38 of the canister being gripped by arms 39.

As each canister support approaches the operator's station, stationary cam 44 engages roller 43 and lowers canister support 33. After each canister 15 is in position, continued rotation of carrier 6 moves roller 43 away from cam 44, and each canister support 33 moves upwardly due to spring 35, seating the open upper rim of the canister in cup 16. Cam 61 then engages roller 23 and valve 19 is pulled outward to open position.

The granular absorbent is fed by gravity through opening 13 into boxes 14, thence through openings in plates 17 and 18 and cup 16 into the canister. Electromagnetic vibrator 31 will vertically vibrate carrier 6 and nine of the ten canister supports, the tenth support being lowered from the carrier and will not be vibrated. Thus the absorbent packed by vibration in the

canister will not be disturbed when the canister has reached the operator's station.

After a filled canister has been removed, an empty one is slipped into place. Rotation of carrier 6 moves the empty canister so that the roller 43 on its support clears cam 44 and spring 35 then moves the carrier 33 upward. The upper rim of canister 15 seats into cup 16 ready for filling.

Further rotation causes valve roller 23 to engage cam 61, pulling valve 19 open. The absorbent then passes through plates 17 and 18 and the openings 20 in cup 16 into the canister. Openings 20 cause the absorbent to be distributed into the canister. The valve remains open and the canister is vertically vibrated to settle and pack the absorbent firmly into the canister.

It will be seen that rotation of carrier 6 is continuous and all canisters except one are being continuously vibrated. This vibration during filling results in packing the granular materials so that subsequent channeling is avoided.

It will be understood that the invention is not limited to the details shown herein by way of illustration, since variations may be made therein by those skilled in the art without departing from the spirit of the invention nor exceeding the scope of the appended claims.

I claim:

1. A machine for filling and packing granular absorbents into gas mask canisters comprising a rotary carrier, means for supporting a plurality of canisters beneath said carrier, means for continuously vertically vibrating said carrier and canisters throughout its complete rotation, said carrier having an opening in alignment with each canister for passing granular absorbents into the canister, a cut-off valve for each opening, stationary means engageable with each valve during rotation of said carrier to open and to close each valve, and means to lower each canister away from its filling opening in response to rotary movement of said carrier.

2. The invention as defined in claim 1, wherein the means to lower each canister comprises a cam positioned between the stationary means to engage each valve.

3. A machine for filling and packing granular absorbents into gas mask canisters comprising a perforated horizontally rotary carrier, means to vertically vibrate said carrier, a canister support beneath each perforation, each support being vertically slidable on a shaft carried by the rotary carrier, valved feeding means for dropping granular absorbents into the canister, and means operative during a minor portion of the travel of said canister about the center of said carrier to successively lower each canister support as the carrier rotates.

4. The invention as defined in claim 3, wherein in each canister support is spring-pressed upwardly to hold its canister in engagement with the carrier.

5. The invention as defined in claim 3, wherein each canister support is spring-pressed upwardly to hold its canister in engagement with the carrier, and the means to successively lower each canister support comprises a stationary cam for engaging and lowering each support against tension of its spring.

6. A machine for filling and packing granular absorbents into gas mask canisters, comprising a horizontally rotary carrier, electromagnetic means to vertically vibrate said carrier, a plurality of perforated filling cups on said carrier,

an absorbent container above said filling cups, a slide valve for closing communication between each cup and container, stationary cams engageable with said valves to open and close the same as the carrier is rotated, a canister support beneath each filling cup and adapted to hold the open upper end of a canister against said filling cup, and means to successively lower each canister support and canister as the carrier rotates.

7. The invention as defined in claim 6, wherein each canister support is slidable upon a shaft depending from the rotary carrier, and each support is pressed upwardly by a spring.

8. The invention as defined in claim 6, wherein the means to successively lower each canister comprises a cam having ascending and descending surfaces connected by a level surface, positioned to engage a part on each canister support.

9. A machine for filling and packing granular absorbent material into gas mask canisters comprising a horizontally rotary carrier, means for supporting a plurality of canisters beneath said carrier and rotatable therewith, a plurality of filling cups supported on the upper surface of said carrier, each cup being vertically aligned with a canister, an annular feed hopper carried by said carrier and communicating with each cup, a sliding gate valve between each cup and its canister, cams to open and close each gate valve in response to rotation of the carrier, springs on said carrier to press each canister upwardly into engagement beneath its cup, and means responsive to rotation of said carrier to pull each canister downwardly and out of engagement with its cup.

10. The invention as defined in claim 9 wherein means are provided for vertically vibrating the rotating carrier, filling cups, feed hopper and the raised canisters.

11. In a filling machine of the class described, a carrier mounted for rotary movement and embodying a circular series of spaced valves each of which includes a slide shiftable in a plane radial to the axis of said carrier, a pair of spaced cams overlying the carrier, one of said cams having a rigid cam surface and the other of said cams having a resilient cam surface, and each valve slide equipped with an instrumentality engageable with the respective cam surfaces to effect sliding movement of the slide first in one direction and then in an opposite direction, whereby said valves are successively opened and closed during rotary movement of said carrier.

12. In a filling machine of the class described, a carrier mounted for rotary and vibratory movements and equipped with a series of valves equidistantly spaced apart and respectively provided with a slide having a cam-contact element, fixed cams overlying said carrier, one of said cams having a rigid cam surface with which the cam-contact element of the respective valves coacts to effect an opening of the valve, and the other of said cams having a resilient cam surface for co-action with the cam-contact element to effect a closing of the valve; and the cam-contact element of each valve and the cam surface of each cam being disposed in such a plane relative to the plane of the carrier and also so proportioned in depth as to maintain contact between a cam-contact element and a cam surface during vibratory action of the carrier.

STUART M. JESSOP.
